UNITED STATES PATENT OFFICE.

JACOB M. KINSEY AND FRANK P. W. YOUNG, OF ST. LOUIS, MISSOURI, AS
SIGNORS OF ONE-FOURTH TO OLIVER M. KINSEY, OF SAME PLACE.

RAIL-JOINT NUT-LOCK.

SPECIFICATION forming part of Letters Patent No. 617,579, dated January 10, 1899.

Application filed August 22, 1898. Serial No. 689,240. (No model.)

To all whom it may concern:

Be it known that we, JACOB M. KINSEY and FRANK P. W. YOUNG, of the city of St. Louis, State of Missouri, have invented certain new 5 and useful Improvements in Rail-Joint Nut-Locks, of which the following is a full, clear, and exact description, reference being had to the accompanying drawings, forming a part thereof.

10 Our invention relates to rail-joint nut-locks; and it consists of the novel construction, combination, and arrangement of parts hereinafter shown, described, and claimed.

Figure 1 is a side elevation of the meeting 15 ends of two rails, the same having our invention applied thereto. Fig. 2 is an enlarged vertical sectional view taken approximately on the line 2 2 of Fig. 1. Fig. 3 is a view in perspective of the under side of one 20 end of the plate made use of in carrying out our invention. Fig. 4 is an enlarged vertical sectional view taken approximately on the lines 4 4 of Figs. 1 and 2.

Referring by numerals to the accompanying 25 drawings, 1 1 indicate the rails, which are of the usual construction, and 2 the fish-plates. One of these fish-plates is of the usual form and construction, and the opposite fish-plate is provided on the top of the laterally-projecting flange with a flat horizontal surface 3, and extending longitudinally throughout this 30 surface and formed in the flange of the fish-plate is a rectangular groove 4. Formed integral with the top surface of one end of the flange having this surface 3 is a lug 5.

6 indicates a rectangular metallic bar that lies directly upon the flat surface 3, and formed integral with the under side of said bar is a rib 7, which occupies the groove 4. 40 Formed in the under side of one end of this plate 6 is a recess 8, into which the lug 5 projects when the plate 6 is located upon the

flange. After the bolts 9 have been passed through the bolt-holes in the ends of the rails and through the fish-plates and the nuts 10 45 are located upon the screw-threaded ends of said bolts the plate 6 is placed in position upon the flat surface of the flange and the fish-plate by sliding it in from one end thereof, and as said plate can only be in this position when the nuts are turned so that their flat surfaces are parallel with the surface of the plate it will be seen how said plate forms a perfect lock for said nuts and prevents them turning upon the bolts. The plate 6 is prevented from leaving the flange of the fish-plate for the reason that the rib or flange 7 55 engages in the groove 4, and said plate is prevented from longitudinal movement, owing to the location of the lug 5 within the recess 8. 60

A rail-joint nut-lock of our improved construction is simple, inexpensive, very efficient, and is readily applied for use.

We claim—

A rail-joint nut-lock, constructed with a 65 fish-plate having a flat surface formed on its horizontal member and there being a longitudinally-extending groove formed in said fish-plate, a lug formed integral with the top surface of said fish-plate, a plate located upon 70 said flat surface, a flange integral with the under side of said plate and occupying the longitudinally-extending groove, and there being a recess formed in one end of the under side of said plate to receive the lug of the 75 fish-plate, substantially as specified.

In testimony whereof we affix our signatures in presence of two witnesses.

JACOB M. KINSEY.
FRANK P. W. YOUNG.

Witnesses:

M. P. SMITH,
MAUDE GRIFFIN.
